UNITED STATES PATENT OFFICE.

EDWARD P. TABOR, OF WORCESTER, MASSACHUSETTS.

FOLDING FAN.

Application filed May 29, 1925. Serial No. 33,743.

To all whom it may concern:

Be it known that I, EDWARD P. TABOR, a citizen of the United States, residing at Worcester, in the county of Worcester and 5 State of Massachusetts, have invented a new and useful Folding Fan, of which the following is a specification.

This invention relates to foldable or collapsible fans for the use of travelers or for 10 home use.

The object of the invention is to provide a fan of this character which when not in use may be folded into a small compact package to occupy a minimum amount of space 15 and which may be readily opened up for use when desired.

With the foregoing and other objects in view which will appear as the description proceeds, the invention resides in the combination and 20 arrangement of parts and in the details of construction hereinafter described and claimed, it being understood that changes in the precise embodiment of the invention herein disclosed may be made within the 25 scope of what is claimed without departing from the spirit of the invention.

In the accompanying drawings:—

Figure 1 represents a longitudinal section of the fan constructed in accordance with 30 this invention shown in open position in full lines and in collapsed position in dotted lines;

Fig. 2 is a front elevation thereof with the fan in open operative position;

Fig. 3 is a transverse section taken on the line 3—3 of Fig. 1; and

Fig. 4 is a detail end elevation.

In the embodiment illustrated a motor 1 is shown housed within a cylindrical shell 40 or casing 2 which may be constructed of any suitable material and which operates as a protective cover for the fan blades and guards when not in use.

A hinged leg 3 is secured to the front 45 end of the shell 2 while a removable leg 4 extends through an opening 5 in the rear of shell 2 and is secured to the motor 1 by a bolt 6 equipped with a wing nut 7.

The cover or shell 2 is slidable over the 50 motor 1 and is equipped with a spring pressed latch 8 having a nose 9 which is designed to extend through apertures in the casing and to engage corresponding apertures in the motor casing as is shown clearly in Fig. 1 for locking the casing in projected or retracted position.

The fan shaft 10 which is operated by the motor projects beyond the front end of the motor and carries thereon a hub 11 having radiating arms 12, four of which are 60 shown and to which the fan blades 13 are hingedly connected. These arms 12 have seats in their front faces and in their ends to receive the fan blades so as to permit them to swing forwardly into the dotted line 65 position shown in Fig. 1 when not in use and when opened up for use they will abut against the rear walls of these seats and hold them in position for use.

To hold the fan blades in operative position within their seats, a slidable blade support 14 is mounted on the shaft 10 in front of the hub 11 and is equipped on its inner end with radiating arms 15, four being here shown corresponding to the number of fan 75 blades used. These arms 15 have longitudinally extending slots or grooves 16 in their faces which are opposed to the blades 13 so as to receive therein the edges of the blades as is shown clearly in Figs. 1 and 3. 80 This sleeve or collar 14 is yieldably held engaged with the fan blades by means of a coiled spring 17 located on the outer end of shaft 10 between the end of the collar 14 and a cap 18 which is secured in adjusted 85 position by a nut 19.

The fan blade supporting collar or sleeve 14 is both rotatable and slidable on the shaft 10 and is held in adjusted position by the nut 19 and the spring 17 so that when it is 90 desired to collapse the fan this collar is moved outwardly and turned to permit the blades to swing downwardly into the dotted line position shown in Fig. 1.

A plurality of fan blade guards 20 are 95 hinged to a casting 21 carried by the front end of the motor and when the casing 2 is slipped backward into the position shown in full lines in Fig. 1 these guards open up into the position shown in said Fig. 1 and 100 in Fig. 2. When the casing 2 is moved forward they fold downwardly into the casing into the dotted line position shown in Fig. 1.

In the use of this collapsible fan the legs or supports 3 and 4 may be folded to lie flat 105 against the casing and when the spring pressed latch or catch 8 is disengaged from the casing and the casing slipped forwardly into the dotted line position shown in Fig. 1 the fan blades and the guards 20 will fold 110 forwardly into the dotted line position and the spring pressed catch 8 is then released.

and engaged again with the motor which holds the casing in this position. The cylindrical casing may then be stored in a very small space.

5. When it is desired to use the fan the above operation is reversed.

I claim:—

1. A collapsible fan comprising a shell, a motor mounted in said shell and on which 10 the shell is slideable, foldable fan blades carried at the front end of the motor, means for holding said blades in open position when the casing is retracted, and means for holding the casing in projected and retracted 15 position.

2. In a collapsible electric fan, the combination of a motor, a shell or casing slideably mounted on and encompassing said motor, spring pressed latches for holding said 20 casing in projected or retracted position, foldable fan blades mounted at the front ends of the motor, and yieldable means for holding said blades in open position.

3. A collapsible electric fan comprising a 25 motor, an operating shaft extending forwardly therefrom, a hub mounted on said shaft and having fan blades radiating therefrom, said blades being foldable, a spring pressed collar mounted on said shaft and 30 having fingers to engage said blades to hold them in open position, said collar being movable to disengage said fingers from said

blades, and a casing slideable on said motor and adapted to move forwardly, whereby the blades are folded therein and held in collapsed position. 35

4. A collapsible electric fan comprising a motor, a shell slideably mounted on said motor and encompassing it, an operating shaft projecting forwardly from said motor, pivotally mounted fan blades carried by said shaft, means for limiting the opening movement of said blades, and a longitudinally slideable rotatable collar mounted on said shaft and having fingers provided with seats 45 to engage said blades to hold them against folding movement in forward position, and yieldable means for holding said fingers engaged with said blades. 50

5. In a fan of the class described, a motor, a shell encompassing said motor and slideable longitudinally thereof, means for holding said shell in projected and retracted position, foldable fan blades carried by said 55 motor, and adapted to be housed within said shell when in projected position, and foldable fan blade guards also mounted in front of said motor and adapted to be folded within the casing in its projected position.

In testimony that I claim the foregoing 60 as my own, I have hereto affixed my signature.

EDWARD P. TABOR.
